UNITED STATES PATENT OFFICE.

WILLIAM McCORKINDALE AND HENRY C. AVERY, OF HOLYOKE, MASSACHUSETTS.

PAPER-PACKAGE.

1,270,248.

Specification of Letters Patent. Patented June 18, 1918.

Application filed January 8, 1916. Serial No. 70,943.

To all whom it may concern:

Be it known that we, WILLIAM McCORKINDALE and HENRY C. AVERY, citizens of the United States of America, residing in the city of Holyoke, county of Hampden, and State of Massachusetts, have invented certain new and useful Improvements in Paper-Packages, of which the following is a specification.

10 This invention relates to improvements in packages of paper, towels and the like and particularly to an improved form of package adapted to coöperate in an efficient manner with a single special form of dispenser such 15 as is disclosed in U. S. Letters Patent No. 1,185,813, issued June 6, 1916.

Manufacturers of paper towels, and the like, ordinarily supply dispensing devices containing their trademark under the assumption that the paper used in the dispenser or container will be invariably of their own make. It has been found in practice, however, that after one manufacturer has placed 20 on the market thousands of dispensers at 25 cost or less, another manufacturer makes a package which will fit these dispensers and sells at a cut price because a large and ready market is available wherever dispensers are installed.

30 Applicants disclose herein an improved form of package which is adapted for use with an improved form of dispenser, which is also disclosed herein but particularly claimed in the above noted patent. The

35 package and dispenser are mutually dependent, as the package is made for use with the dispenser alone and the latter is made to receive only the improved form of package. By thus combining the dependent features 40 of both the dispenser and package, the desired result is obtained, of insuring the use of one brand of paper in the dispenser. The manufacturer is, therefore, enabled to build up his trade on a safe basis, without the continual annoyance of unfair competition from 45 other manufacturers. Aside from the advantages of the invention noted above, there are inherent advantages in the structure.

An object of the invention is to provide 50 an improved and specially formed package which may only be inserted in a single specially formed type of dispenser.

55 Another object is to provide an improved form of package which is of extreme simplicity and is arranged to coöperate in an efficient manner with its dispenser.

Other detailed objects of the invention will appear in the following description and annexed claims.

Referring to the drawings as illustrating 60 one manner in which the invention may be carried out—

Figure 1 is a front view of the dispenser with a part broken away to show the improved package assembled in position for 65 operation.

Fig. 2 is a cross sectional view taken on the lines 2—2 of Fig. 1.

Fig. 3 is a cross sectional view of a modified form of the dispenser. 70

Fig. 4 is a detail view showing one manner of holding together the special package of sheets.

Fig. 5 is another form of the same.

Fig. 6 is another form, and 75

Fig. 7 is still another form of holding the package.

The invention is, as shown, arranged for use with a special container or casing called the dispenser, which may, if desired, be 80 entirely closed except at one end. In this dispenser it is not necessary to have any other opening than the end opening mentioned. In other words, the dispenser may be made with all of its walls fastened together permanently. The open end of the dispenser is of a suitable size to receive the package of sheets when the latter is inserted directly therein. In the dispenser means are provided to coöperate with suitable devices contained on the package to receive and hold the latter in position after it has once been inserted in such a manner that it cannot be ordinarily removed from the dispenser after it has once been inserted. 95

The engagement of the means within the dispenser with the devices on the package is designed to occur in an automatic manner, so that no knowledge of the detailed operation of the dispenser is necessary. After the 100 sheets have been pulled from the package one by one until the package has been exhausted, then it is possible to loosen the holding devices of the package in the dispenser and insert a new package. The invention 105 as outlined may be carried out in various forms.

The preferred form is disclosed in Figs. 1, 2 and 4. Referring to Fig. 2, the dispenser comprises, as shown, a rectangular 110 closed casing *a* open at the bottom only. The walls of this casing are preferably fastened

together permanently. At some distance from the bottom of the casing and preferably about midway of the front and rear walls and arranged centrally are two metal brackets each made up of two V-shaped spaced vertical walls *b*, connected by the slanting wall *c*, with the points of the V extending downwardly. These brackets, as shown, are soldered one on the front wall and one on the rear, in the position approximately as shown in Figs. 1 and 2. This is all there is to the dispenser and it is seen that it is of extreme simplicity and extremely economical to manufacture.

Referring now to the special form of package with which this application is more directly concerned, it may be said that the package is generally like that disclosed in patent to Teall 1,131,874 dated March 16, 1915. This package comprises in its preferred form a stiffening cardboard center *f* around which a pack of assembled sheets is folded. These sheets are pasted one to the other in the so-called drop formation. The ends of the pack are brought together as disclosed in Figs. 2 and 4 and are provided with two vertical cuts *g* (see Fig. 1). These cuts are spaced apart, as shown, and provide a plane of weakness for the sheets to be torn from the pack as the ends are held by the holding strip *i*. Strip *i*, made of pliable metal, is looped, one strip through each end and over the top of the pack. The ends of each strip are bent into overlapping relation against the upper end of the stiffening piece *f*. These strips project beyond the sides of the pack as shown at *k* for a purpose to be described.

With the package formed as shown and described it is inserted in the dispenser by directly pushing its upper end in the open end of the casing *a*. The projections *k*, of metal strips *i*, one on the front and one on the rear sides of the package, engage the sloping walls *c* of the brackets above mentioned, which force the upper end of the package tightly together as it is pushed upwardly in the container. As soon as the projections *k* leave the upper end of the sloping wall *c* the compression just mentioned causes the projections *k* to spring outwardly. If the package is then released, it will settle down into the position shown in Fig. 2, so that the projections *k* extend in overlapping relation to the upper sloping walls *c* and between the V-shaped walls *b* of the dispenser brackets. In this position it is impossible for any one to reach their hand up inside of the casing and release the package from the brackets. The engagement of the devices *k* of the package with the means *c* of the dispenser as described is automatic. A single sheet *e* may be pulled from the package in the manner customary with "drop down" sheet packages, and will

bring the end of the attached sheet into accessible position after which the sheet *e* is pulled from the sheet to which it is attached. The sheets are thus pulled one by one from the package until the latter is exhausted at which time it is possible to insert one's hand in the casing, pull the holding or binding device or strips *i* away from the brackets and out of the casing for the next package to be inserted.

It will thus be seen that an extremely simple and economical dispenser for the type of package disclosed is provided which has the advantage that a special form of package is required and thus the insertion of foreign packages prevented. It will also be seen that the means for fastening the package in the dispenser is automatic and extremely simple, and constitutes a new and useful device.

In Fig. 3 a modified form of the dispenser is shown. The casing 1 corresponds to the casing *a*, shown in Fig. 2. Instead of providing the brackets, as shown in Fig. 2 in this modification, the springs 2 sloping upwardly from the front and rear walls of the dispenser are provided. When a package such as shown in either of Figs. 4 to 7 is inserted in the casing 1, the springs 2 will be bent backwardly against the walls of the casing until the projections *k* are above the level of the top of the springs, at which time the latter will move back toward the position shown in Fig. 3 and engage under the projections *k* to hold the package in the manner similar to that described, in connection with Fig. 2. Where the springs 2 yield, to allow the package to be inserted in the casing it is not necessary for the package to be compressed to any considerable extent. Where crape tissue paper is used, the package is very easily compressed and has considerable resiliency so that it will operate efficiently with the casing as shown in Fig. 2.

In Fig. 5, a modified form of holding means for the ends of the sheets is shown. In this form a single metal wire *m* is threaded through both ends of the package and the ends of this metal wire are brought together at the upper end of the package and twisted as shown at *n*. Bound over the top of the package in a V-shaped form is a metal strip *l* having projections *s* corresponding to the projections *k* shown in Fig. 4. This V-shaped metal strip *l* is held in place by means of the wire *m* which passes through the strip and over the top thereof, as indicated in the figure.

In Fig. 6 another modification is shown, in which a metal strip *u* is threaded through holes at both ends of the package and is provided with projections *v* corresponding to projections *k*. At the lower ends of this strip *u* there are holes through which a tape *t* is passed and brought up over the ends of

the package. There is one tape on each side of the package and both are tied into a knot at y . This tape and the manner of its connection with the strip u tends to force the strip apart. This increases the tendency for the projections v to enter over the ends of the walls c or the springs 2. 5

In Fig. 7, still another modification is shown, which is essentially similar to the one disclosed in Fig. 4 with this difference, that instead of the ends of the strips o which in Fig. 4 have their equivalent in the strips i , being bent as disclosed at j in Fig. 4 they are brought into parallel relation 15 against the stiffening strip f and a rivet p is passed through the ends to bind them together. The projections q correspond to the projections k in every way.

It is recognized that many other modifications of the package may be made and that the various forms of packages embodying the invention may be constructed and applied to various forms of dispensers. The scope of the invention is, therefore, defined 20 more accurately in the following claims than in the detailed description of one or more preferred forms.

What we claim is:

1. A package of towels formed to closely fit within a casing having a single opening and arranged when inserted to close said opening and yieldable holding devices on the package arranged when the package is pushed into the casing to automatically snap 30 into engagement with devices within the casing to support the package therein.

2. A package of towels or the like adapted to substantially fill an open ended casing and means on the package automatically 40 movable relatively thereto by the insertion of the package in said casing, and thereafter automatically movable in an opposite direction to engage parts of the latter and support the package so that it cannot be removed until substantially consumed.

3. A package of towels or the like adapted to substantially fill a container and having means thereon compressible by parts of the casing as the package is inserted therein and 50 thereafter expandable on further insertion of the package to spread into supporting engagement with said parts.

4. A package of towels adapted to substantially fill a container and having movable means on opposite sides of the package

and automatically operable as the package is pushed into the container to spring into supporting engagement therewith, said means constructed and arranged to prevent removal of the package until it is substantially used up. 60

5. A towel package, for use with a dispenser having a single open end, made to substantially fill the dispenser and when inserted therein to close said open end, and means on the package operable as the latter is inserted in the dispenser to automatically engage a part thereof, said means and part being relatively movable in one direction by the insertion of the package in another direction and relatively movable in an opposite direction after the package has been positioned in the dispenser to prevent removal of the package from the latter. 70

6. A towel package comprising a plurality 75 of sheets packed one on the other, a supporting member from which the upper ends of the sheets are hung and projections extending downwardly from said member beyond the sides of the package arranged to automatically engage supporting members in a dispenser.

7. A towel package comprising a plurality of sheets packed one on the other, a supporting member from which the upper ends 85 of the sheets are hung and projections extending downwardly in diverging relation from said member beyond the sides of the package to automatically engage supporting devices on the casing, said projections and member being constructed and arranged to yield as the package is moved past said devices in one direction and to snap past the latter to prevent movement of the package 90 in the other direction. 95

8. A package of towels made to substantially fill a container, comprising, a plurality of sheets packed one on the other, and supporting means for said sheets including projections extending downwardly beyond and 100 in inclined relation to the sides of the package, said projections constructed and arranged to automatically engage with a part of the container when the package is inserted therein and to grip said part to prevent removal of the package from the container. 105
